UNITED STATES PATENT OFFICE.

VICTOR H. JENNINGS, OF WORCESTER, MASSACHUSETTS, ASSIGNOR, BY MESNE ASSIGNMENTS, TO FRANK R. BATCHELDER, OF WORCESTER, MASSACHUSETTS.

WOVEN POCKETED CARRIER.

1,373,739.

Specification of Letters Patent. Patented Apr. 5, 1921.

Application filed August 8, 1918. Serial No. 248,872.

To all whom it may concern:

Be it known that I, VICTOR H. JENNINGS, a citizen of the United States, residing at Worcester, in the county of Worcester, State 5 of Massachusetts, have invented a certain new and useful Improvement in Woven Pocketed Carriers, of which the following is a specification, reference being had therein to the accompanying drawings.

10 The invention is applicable in connection with woven pocketed carriers pertaining to military equipment and the like, but is not restricted thereto. It is adapted to be utilized in the production of the pockets of 15 cartridge carriers, or in that of larger pockets of carriers designed for different uses.

The invention has relation to woven carriers of those classes which have pockets of somewhat bulging shape and relatively 20 large internal capacity, adapted for instance in the case of a pocket of a cartridge carrier to contain two or more clips of cartridges, secured by forming the body of a pocket of sufficient fullness to enable the pocket 25 to expand somewhat widely in the direction from rear to front across the entire breadth thereof into substantially rectangular horizontal cross-section.

The pocketed webs of which carriers of 30 the said classes have been made heretofore are produced by somewhat involved special processes of weaving, and through the employment of special loom-mechanism, the rate of production unavoidably being small, 35 and the cost of production relatively large.

Stated in general terms, the invention 40 consists in a woven carrier having a pocket or pockets of novel construction, and in a novel method of making pocketed carriers, the said novel construction and novel method being of a character which simplifies the weaving operations, enables certain special loom-appliances to be dispensed with, facilitates production of pocketed carriers, 45 enables the output thereof to be greatly increased, and lowers the cost materially.

More specifically, my improved woven carrier, it having the front and back walls of its pocket united at the opposite sides of 50 the pocket by interweaving, as heretofore, is characterized by having one of said walls formed into one or more plaits on vertical lines, whereby it is shortened transversely of the pocket and thereby the other wall is

given fullness to constitute a bulging body- 55 portion adapted to expand across the breadth thereof into substantially rectangular horizontal cross-section. My improved method of making pocketed carriers consists in weaving a carrier-web composed of 60 single-cloth and double-cloth sections in alternating sequence, and forming one or more plaits in one of the cloths of a double-cloth section and fastening such plait or plaits, thereby narrowing such cloth and giving the 65 said fullness to the other cloth for the purpose first mentioned.

The drawings show various ways of reducing the invention to practice.

Figure 1 is an isometric view showing 70 one pocket of a pocketed carrier having plaits at both sides thereof, with said plaits fastened to the backs of the single-cloth sections, the face of the carrier being turned 75 toward the front of the view.

Fig. 2 is an isometric view of the pocket of Fig. 1 with its back turned toward the front of the view.

Fig. 3 is a plan view of the said carrier.

Fig. 4 shows in edge view a portion of 80 carrier-web sufficient for the production of the pocket of Figs. 1, 2 and 3.

Figs. 5 and 6, respectively, are views in cross-section on lines 5—5 and 6—6, respectively, in Fig. 4.

Figs. 7, 8 and 9 are front, back, and plan views of a pocket having a different disposition of plaits at the opposite sides thereof, and Fig. 10 is a view in vertical section on line 10—10 of Fig. 9.

Figs. 11 and 12 are front and back views of pockets having a single intermediately located plait. Fig. 13 shows the carrier-web from which such pocket is made, and Figs. 14 and 15 are views in vertical section on 95 lines 14—14 and 15—15, Fig. 13.

Figs. 16 and 17 are, respectively, a front view and a back view of another pocket having a single plait, Fig. 18 is a view of the carrier-web that is used in making the said 100 pocket, and Fig. 19 is a view in section on line 19—19 of Fig. 18 on a slightly enlarged scale.

Having reference to the drawings,—

Figs. 1, 2 and 3, and other like views, 105 show a single pocket-unit, intended as one of the pocket-units of a carrier composed of a plurality of such units disposed in line

with one another. The invention is applicable equally in the case of carriers which in their finished state have but one pocket.

In Figs. 1, 2 and 3, the pocket-back, which 5 extends straight across the pocket from side to side of the latter, is marked 1, and 2 is the pocket-front, having the fullness which causes it to bulge forwardly, as hereinbefore indicated. At 3, 3, are web-portions, 10 at opposite sides of the pocket, in which the warp-threads of the pocket-front and pocket-back are interwoven to unite these latter at the said sides. In a carrier-web, and in a finished carrier having a plurality of 15 pockets, these portions 3, 3, constitute the connective portions between successive pockets. For convenience of designation, the section comprising the portions 1, 2, will be mentioned herein in some cases as a double-cloth section, by reason of being composed 20 of two cloths side by side, and the portions 3, 3, will be mentioned as single-cloth sections, by reason of being of unseparated structure, as indicated in Fig. 6, no limitations 25 as to the number of plies in either thereof being intended. As usual, the pocket-back and pocket-front are joined together along the bottom 4 of the pocket in the weaving, to close the pocket at its bottom. As usual, also, at the top of the pocket 30 the pocket-back and pocket-front are woven with separate margins to constitute the open pocket-mouth.

Substantially the usual method of producing carriers of the class to which the invention is applicable is disclosed in U. S. Letters Patent to T. C. Orndorff, for woven cartridge belt, No. 666,687, granted under date of Jan. 29, 1901. The carrier of the said 40 patent is a cartridge-belt composed of a multiply fabric woven with pockets to accommodate clips of cartridges, and having the bodies of the pockets formed from the outer ply of the multiply fabric by weaving said 45 ply at intervals separate from the inner ply, with a fullness sufficiently great to give capacity to receive the desired number of clips. The said fullness in the portions of the outer 50 ply which form bodies of the pockets is secured by placing a greater number of picks of weft or filling in the said ply (constituting the pocket-front) than in the inner ply (constituting the pocket-back)—as for example, four picks in the outer ply to each 55 two in the inner ply. As already indicated herein, this procedure not only involves a special mode of weaving, but in practice necessitates the use of special devices in the loom in which the weaving is performed, to 60 take care of the fullness and meet the different requirements in connection with the pocket-front and pocket-back.

In accordance with the invention, I weave the carrier-web with the back and front

cloths 1 and 2 of a pocket-unit equal in 65 length with each other, as shown in Fig. 4, between the lines on which they are interwoven with each other, or substantially equal. I then shorten the back cloth transversely of the pocket by forming one or 70 more plaits therein on vertical lines, and fasten such plaits. In Figs. 1, 2 and 3, the plaits a , a , are formed at the opposite sides of the pocket, by bending portions of the pocket-back in outward directions against 75 the backs of the connective portions 3, 3, and are secured against such backs by means of vertical lines b , b , of fastenings, usually 80 stitches. The extent of the resulting fullness of the pocket-front 2, and consequent 85 bulge of the latter, is determined by the amount of material pertaining to the pocket-back that is taken up in the plaits, and the consequent shortening of the pocket-back.

In Figs. 7, 8, 9 and 10 the plaits a' , a' , are 90 formed at the opposite sides of the pocket by bending portions, 3^a , 3^a , of the connective portions 3, 3, sharply forward and securing the adjacent portions of pocket-back 1 by 95 vertical lines of fastenings b' (stitches) against the inner sides of the said forwardly bent portions 3^a , 3^a . This construction has an advantage in that the sides of the pocket are stiffened and the pocket keeps its shape better.

In Fig. 11 a single large plait a^2 is formed 95 in the intermediate portion of the back 1 and secured by lines of fastenings b^2 , b^2 , along each of the folds thereof.

In some cases, in order to enable the material at the lower end of a plait to be more easily and smoothly laid in place, a slit as at c , Figs. 13 and 15, may be produced in the bottom of the pocket in the weaving process, or may be cut therein after the weaving has 100 been completed. In finishing the pocket, the free edge, c' , Figs. 12 and 13, of the pocket-front at such slit will be secured by stitches or otherwise. Fig. 13 shows in dotted lines 105 the partially-formed plait a^2 , and the corresponding pucker or gather that is formed in the pocket-front.

Figs. 16 to 19 illustrate the application of 110 the single plait a^2 to the pocket-back of a pocket having the bottom thereof produced with an infold g , Fig. 19, for the purpose of securing increased capacity in the lower part of the pocket.

What is claimed as the invention is,—

1. A woven pocketed carrier having the 115 front and back walls of its pocket equal in width and united at the opposite sides of the pocket by being interwoven, and also having one of said walls permanently secured in plaited shape by applied fastening means 120 and thereby shortened transversely, whereby the other wall is given fullness to constitute a bulging body-portion adapted to

expand across the breadth thereof to give the pocket a substantially rectangular cross-section.

2. A woven pocketed carrier having the front and back walls of its pocket equal in width and united at the opposite sides of the pocket by being interwoven, and both thereof containing substantially the same length of material between the places where they are interwoven with each other, with one of said walls permanently secured in plaited shape by applied fastening means and thereby shortened transversely, whereby the other wall is given fullness to constitute a bulging body-portion adapted to expand across the breadth thereof to give the pocket a substantially rectangular cross-section.

3. A woven pocketed carrier having the front and back walls of its pocket equal in width and united at the opposite sides of the pocket by being interwoven, and also having one of said walls permanently secured in plaits by applied fastening means at both of said sides and thereby shortened

transversely, whereby the other wall is given fullness to constitute a bulging body-portion adapted to expand across the breadth thereof into substantially rectangular cross-section.

4. The method of making pocketed carriers which consists in weaving a carrier-web composed of single-cloth and double-cloth sections in alternating sequence, forming one or more plaits in one of the cloths of the double-cloth section, and permanently fastening such plait or plaits by the application of fastening means, whereby such cloth is narrowed and fullness is given to the other to constitute a bulging body-portion adapted to expand across the breadth thereof into substantially rectangular cross-section.

In testimony whereof I affix my signature in presence of two witnesses.

VICTOR H. JENNINGS.

Witnesses:

FLORENCE K. BERRY,
FLORENCE M. RUSSELL.

It is hereby certified that Letters Patent No. 1,373,739, granted April 5, 1921, upon the application of Victor H. Jennings, of Worcester, Massachusetts, for an improvement in "Woven Pocketed Carriers," were erroneously issued to Frank R. Batchelder, whereas said Letters Patent should have been issued to *Mills Belt Company, of Worcester, Massachusetts, a Corporation of Massachusetts*, said corporation being assignee, by *mesne assignments*, of the entire interest in said invention, as shown by the records of assignments in this office; and that the said Letters Patent should be read with this correction therein that the same may conform to the record of the case in the Patent Office.

Signed and sealed this 17th day of May, A. D., 1921.
